APPARATUS FOR WAXING COLLAPSIBLE TUBES

Dominic J. Palermo, Brooklyn, N. Y., assignor to
 Victor Industries Corporation, Brooklyn, N. Y.,
 a corporation of New York

Application September 2, 1947, Serial No. 771,741

4 Claims. (Cl. 91—44)

1

This invention relates to the apparatus for waxing the interior of collapsible tubes and particularly to insuring a uniform coating on the tube.

Collapsible metal tubes of the type designed to hold and to dispense tooth paste or other pasty materials are frequently coated on their interior surfaces with wax or the like materials to resist corrosion of the metal tube and the effect of the metal on the contents. Such tubes have constricted hollow necks through which the contents are dispensed after removal of the cap, and have a tapered or conical shoulder joining the neck to the body of the tube. In coating the inner surfaces of the tube with molten wax, the wax tends to accumulate in the neck by capillary attraction, thereby closing up or clogging the relatively small discharge opening of the neck and preventing the contents of the tube from being dispensed therethrough. The wax may even solidify to form a wall across the neck if given time to cool between operations upon the tube.

The present invention therefore contemplates the provision of means for coating an empty but capped collapsible tube open at its filling end, with wax in such a manner that no wax is retained across the neck of the tube, and the neck as well as the interior walls of the tube are uniformly coated.

The invention further contemplates the provision of a heated spring-pressed and valved spray tube for delivering a stream of heated air at sufficient speed and in sufficient volume and at the required temperature to melt and to distribute evenly any wax which may have accumulated in the neck of a wax-coated tube.

The various objects of the invention will be clear from the description which follows and from the drawings, in which

Fig. 1 is an elevational view of the tube coating, neck freeing and tube heating apparatus designed to perform my new method.

Fig. 2 is a vertical sectional view of the means for directing a stream of heated air into the neck and shoulder of the tube.

Fig. 3 is an enlarged horizontal sectional view of the same taken on the line 3—3 of Fig. 2.

Fig. 4 is a fragmentary vertical sectional view of the upper end of the wax sprayer and of the capped tube, in the positions assumed thereby during the waxing operation, showing how the wax accumulates in and clogs the neck of the tube.

Fig. 5 is a similar view of the hot air sprayer 55 having a flat base 28 spaced slightly below

2

showing the accumulated wax melted and blown out of the neck.

Fig. 6 is a vertical sectional view of the spraying tip on the upper ends of the wax and hot air sprayers, showing the outlet perforations for the fluid and the drain grooves.

In the practical embodiment of the invention shown by way of example, the capped collapsible tube 10 having the cap 11 screwed on to the tube 10 neck 12 and being open at the other end 13 thereof, is mounted on the wax spraying tube 14 as by dropping the collapsible tube around the spraying tube. The conical support 15 fixed to the spraying tube and movable therewith engages the open end 13 of the collapsible tube 10 and transmits to the spraying tube any pressure put upon the collapsible tube to depress said tube, whereby the spraying tube may be moved downwardly by manual pressure on the tube 10. The support 15 is made sufficiently large to protect the lower parts of the mechanism from draining wax. An inlet pipe 16 through which molten wax is forced, communicates with the interior of the spraying tube, which in operation, is close to or touches the shoulder of the collapsible tube. The wax is sprayed into the neck and against the shoulder of the collapsible tube 10 when said tube is depressed to open the valve between the pipe 16 and the spraying tube. Since the tubes for spraying both wax and heated air are substantially of the same construction, a description of one of said tubes will suffice for both.

As best seen in Fig. 2, which shows the air inlet pipe 17 for the supply of air under pressure, a fixed hollow valve member 18, which serves also as a guide for the spraying tube in the movement of the latter, is secured to the inlet pipe and is provided with the fixed valve seat 19 shown as conical and surrounding the valve opening. The similarly shaped valve disc 20 on the spraying tube 21 is normally maintained in its valve closing position, wherein it is seated on the valve disc 19, by the compression spring 22 surrounding and supported by the extension 23 of the spraying tube, the spring abutting at one end against the valve disc and at its other end against the inlet pipe. Inlet holes as 24 are made in the spraying tube above the valve, through which holes fluid passing through the open valve enters the interior of said tube and passes upwardly to the spraying tip 25.

A connecting sleeve 26 receives the major part of the depending sleeve 27 of the spraying tip and terminates at its upper end in an enlargement having a flat base 28 spaced slightly below

the similar base 29 (Fig. 6) of the spraying tip, the lower end of the sleeve being secured to the tube 21, and part of the sleeve 27 being exposed in the space 30 between the bases 28 and 29. A series of holes 31 in the exposed part of the sleeve 27 permit the discharge of fluid into the collapsible tube 10. The upper part of the tip 25 is shaped to contact with the inner face of the conical shoulder 32 of the tube 10 and is sufficiently close to the discharge opening in the neck 12 to discharge fluid through the inclined holes 33 thereof into the neck. In the case now being described, the fluid is air which is heated by the valve member 18 obtaining heat from a suitable electrical heater 34 surrounding the valve member and energized by current lead to the terminals 35, 36 of a suitable electrical plug.

Suitable grooves as 38 depressed in the conical surface of the tip 25 provide draining passages for the excess wax melted by the heated air stream and blown by said stream out of the neck, and permit the molten wax to flow downwardly along the inner surfaces of the neck and shoulder and along the body of the collapsible tube, thereby aiding to coat the inner surfaces completely with a thin layer of wax.

In the case of the wax sprayer tube 14, the heater is omitted, but the valve and the spraying tip are substantially the same as those just described, whereby wax is sprayed through the holes 31 and 33 of the tip when the collapsible tube is mounted on the tube 14 and depressed to open the valve. The wax collects on the inner walls of the neck and shoulder of the collapsible tube, the excess wax above that required for coating, flowing past the tip 25 through the surface grooves thereof to coat the inner surface of the body of the collapsible tube.

The thus waxed tube 10 is then removed from the wax spraying tube 14 and mounted on the hot air spraying tube 21 and depressed, whereby the wax 37 accumulated in the neck, if solidified, is melted, the excess molten wax being blown out of the neck by the blast of air and flowing out of the neck along the surface grooves 38 to become distributed on the inner surfaces of the tube 10. After the wax accumulating in the neck has been blown out as described, the tube 10 is mounted on one of the rods 39 upstanding from the conveyor chain 40 and is carried by said chain into the heated chamber 41 where the tube 10 is heated, thereby assuring an even coating of wax therein, the excess wax draining off the conical support 42 on rod 39. The evenly coated tube is removed from its supporting rod 39 on its emergence from the heated chamber, and the wax is allowed to harden at room temperature.

It will be seen from the above that I have provided a simple, efficient and easily operated apparatus for producing an even coating of wax or the like on the inner surfaces of the neck, shoulder and body of a collapsible tube in spite of the tendency of the wax to accumulate in and to clog the discharge opening in the neck if permitted to do so. It will further be understood that various changes may be made in the specific form of the invention herein illustrated, without departing from the spirit of the invention defined in the appended claims.

I claim:

1. In apparatus for waxing the interior of a collapsible tube having a constricted hollow neck

5
10
15
20
25

and a tapered shoulder, a vertically movable wax sprayer adapted to support a tube and to spray a stream of molten wax into the neck and shoulder of the tube when depressed by downward pressure on a tube supported thereby, a vertically movable hot air sprayer adapted to support the waxed tube and to spray heated air into the neck and shoulder of the tube when depressed by downward pressure on the waxed tube supported thereby, thereby to drain off excess wax accumulated in and tending to clog the neck, and a fixed heater surrounding the lower part of the hot air sprayer to heat the air entering the sprayer.

2. Apparatus according to claim 1 wherein each of the sprayers comprises an upright vertically reciprocable fluid conducting tube, a fixed fluid inlet pipe communicating with the spraying tube, a valve interposed between the interior of the spraying tube and the inlet pipe and comprising a fixed valve seat, a valve disc secured to and movable with the spraying tube and a spring urging the disc against the seat, a spraying tip at the upper end of the spraying tube, said tip being of generally conical outline to fit that portion of the collapsible tube below the neck and being provided with outlet openings and with surface drain grooves.

3. In apparatus for waxing the interior of a collapsible tube, a hot air sprayer adapted to melt and to drain excess wax deposited in the neck of a collapsible tube and tending to clog the neck, said sprayer comprising a spring-pressed and vertically movable tube, a valve disc on the movable tube, a fixed guide sleeve around the lower part of the movable tube, a valve seat on the sleeve adapted normally to seat the disc and thereby to close the valve, a heater around the sleeve, a perforated spraying tip of generally conical form at the top of the movable tube, said tip having a flat base in upward spaced relation to the adjacent end of the movable tube, said tip having a sleeve entering said adjacent end, the last mentioned sleeve having perforations therein inclined upwardly and outwardly and having additional perforations therein between the base and the adjacent end of the movable tube to direct a stream of air against the adjacent surface of the collapsible tube mounted on the movable tube when the collapsible tube is pressed downwardly.

4. Collapsible tube waxing apparatus according to claim 3 wherein the movable tube is provided with holes therethrough above the valve disc and communicating with the interior of the sleeve when the valve disc is in a depressed position a substantial distance below the valve seat, the spraying tip having surface drain grooves therein for the downward flow of molten wax out of the neck of the collapsible tube.

DOMINIC J. PALERMO.
